ARCHIE MACPHAIL NIVEN, OF DETROIT, MICHIGAN, ASSIGNOR TO CONTINENTAL MOTORS CORPORATION, OF DETROIT, MICHIGAN, A CORPORATION OF VIRGINIA

SLEEVE VALVE ENGINE

Application filed November 16, 1927. Serial No. 232,549.

This invention relates to internal combustion engines and refers more particularly to the sleeve valve type of engine. In this type of engine the upper extremity of the sleeve ordinarily works in a pocket formed between the cylinder head and cylinder. While the cylinder head is ordinarily jacketed for cooling water, the amount of available jacketing is limited due to spark plug location and general arrangement of parts. As a result the sleeve jacket tends to become overheated resulting in formation of steam pockets, carbon accumulation and general inefficient operation of the engine.

15 One of the objects of my invention resides in providing means for overcoming the above objectionable characteristics. To this end I have provided improved means associated with the cylinder head for causing a positive 20 circulation of cooling water for cooling the cylinder head, sleeve pocket and spark plug.

A further object of my invention resides in the provision of means for supporting the sealing ring for the cylinder head and water jacket cover by the water circulation means. 25 I have provided a member preferably in the nature of a sheet metal stamping associated with the cylinder head for assisting in guiding the water in the desired circulating path and for also supporting the cylinder head sealing ring.

Further features and advantages of my invention reside in the simplicity of parts, lightness of weight, and ability to be manufactured at low cost.

One additional feature of my invention resides in the provision of a cylinder head having integrally formed radial baffles which extend down into the cylinder head water jacket space and also project upwardly from this space to deflect the cooling water into the space. Such construction eliminates the necessity for aligning cooperating baffles carried by both the cylinder head and the cylinder head cover or other element.

Further features of my invention reside in the novel combination and arrangement of parts more particularly hereinafter described and claimed.

50 Referring to the accompanying drawings

illustrating my invention and in which like reference characters indicate corresponding parts,

Fig. 1 is a sectional elevation view through a typical engine cylinder showing my invention.

55 Fig. 2 is a perspective view showing the assembly of the water circulating element with the cylinder head,

Fig. 3 is a sectional view of a cylinder head corresponding in general to Fig. 1, but illustrating a modification of my invention, and

Fig. 4 is a perspective view of the cylinder head shown in Fig. 3.

60 In the drawings reference character 10 represents an engine cylinder with associated piston 11 and sleeve valve 12, the latter for illustration being shown as the "Burt-McCollum" single sleeve valve type in which the sleeve is moved in a combined reciprocating and oscillating path with respect to the sleeve axis in moving sleeve ports 13 to function with the cylinder ports 14.

65 The cylinder 10 is closed at the top by a cylinder head 15 which is formed with walls 16 and 17. The wall 16 together with the associated cylinder forms a sleeve valve pocket 17^a accommodating the movement of the upper portion of the sleeve valve 12. The wall 17 is spaced from wall 16 to form the cylinder

70 head cooling water jacket 18 and also defines the combustion chamber 19. The wall 17 may be extended to provide a barrel 20 with the spark plug opening 21. The cylinder

75 head 15 may be secured to the cylinder by studs 22 at the corners of the cylinder head flange 23.

78 The cooling water from jacket 24 is open for communication with the cylinder head jacket 18 through opening 25 preferably 80 mainly along one side only of the cylinder head. For guiding the water from opening 25 I have provided a member 26 preferably formed of a sheet metal stamping. The member 26 is formed with wall 27 spaced from the

85 side of the cylinder head adjacent the opening 25, side walls 28, top wall 29, and end wall 30. The top wall 29 has an opening 31 for fitting the member 26 over the barrel 20, in which position it is supported from the

90 95 100

cylinder by the side walls 28 and end walls 27, 30. A sealing ring 32 surrounds barrel 20 and is supported by the top wall 29 of the member 26, this sealing ring forming a water seal joint between barrel 20 and the cylinder head water jacket cover 33. For this purpose the cover 33 has an opening 34^a receiving the barrel 20, a nut 35^a threaded on the barrel serving to seat the cover 33 in position on the cylinder 10 and also serving to seat the sealing ring 32 on the member 26.

The cylinder head 10 has formed therewith the radial baffles 34 which extend downwardly into the cylinder head jacket 18 but terminating short of the bottom of the jacket. The baffles 34 also have portions 35 thereof extending upwardly above the flange 23 and laterally from the jacket 18, the portions 35 terminating closely adjacent the under face of wall 29. The baffles might extend for supporting contact with the wall 29 but I prefer to seat the member 26 as aforesaid, avoiding the necessity for machining the tops of the baffles. The small clearance above the baffles will not materially affect the desired circulation.

In operation the water under pressure from the usual circulating pump (not shown) will pass mainly through opening 25 and will be guided by the member 26 and baffles 34 so as to circulate downwardly into the cylinder head jacket 18 and upwardly thereof on the other side of the baffles, thence through slots or openings 36 in the member 26 to the outlet header 37 which may lead to the usual cooling radiator (not shown). The member 26 also serves to seat the sealing ring 32 permitting the formation of a barrel 20 on cover 33 without the usual circumferential sealing ring supporting flange as is customary at present. At the same time the parts may be readily assembled or disassembled.

Referring to Fig. 3, the member 26 shown in Fig. 1 is eliminated, the sealing ring 32^a being seated by the flange 38 formed with the barrel 20^a as shown or with the cover 33 both being generally in use at this time. In this instance the baffles 34 are constructed generally as shown in Figs. 1 and 2 the tops of the baffles being extended upwardly from flange 23 sufficiently to deflect cooling water into the jacket 18. The baffles 34 extend upwardly to the under side of the cover 33 preferably connecting flange 38. In this modification generally illustrated in Fig. 3 a single baffle formed integrally with the cylinder head provides the circulation of the cooling water downwardly into the cylinder head jacket, other cooperating baffles or water guiding members being dispensed with.

It will be apparent that in the embodiments of my invention shown in Figs. 1 and 3 each has its advantages, certain advantages being common as stated hereinbefore.

In Fig. 3 it will be understood that adja-

cent cylinder heads of adjacent cylinders have their baffle sides substantially contacting so as to substantially align baffle flanges 35 whereby passage of water between adjacent cylinder heads is sufficiently prevented to accomplish the water deflection into the cylinder head jacket.

My invention is equally well adapted for use with various types of sleeve valve engines such as multiple or single sleeves having various movements, the particular sleeve valve provisions forming no part of my invention.

What I claim as my invention is:

1. An internal combustion engine of the sleeve valve type comprising in combination, a water jacketed cylinder, a piston operable therein, a water jacketed cylinder head forming a sleeve pocket with the cylinder and provided with a barrel portion, a cylinder head cover through which said barrel extends, a sealing ring between the barrel and cover, and a member intermediate the cylinder head cover and cylinder head having an opening received by the barrel, said member constructed and arranged to support the sealing ring and to form a water deflecting passage in conjunction with the cylinder head jacket for directing water from the cylinder jacket to flow generally downwardly into and across the cylinder head.

2. An internal combustion engine of the sleeve valve type comprising in combination, a water jacketed cylinder, a piston operable therein, a water jacketed cylinder head forming a sleeve pocket with the cylinder and provided with a barrel portion, a cylinder head cover through which said barrel extends, a sealing ring between the barrel and cover, and a member intermediate the cylinder head cover and cylinder head having an opening received by the barrel, said member constructed and arranged to support the sealing ring and to form a water deflecting passage in conjunction with the cylinder head jacket for directing water from the cylinder jacket to flow generally downwardly into and across the cylinder head, said member provided with water outlet openings.

3. An internal combustion engine of the sleeve valve type comprising a cylinder, a cylinder head having a water jacket portion depending into said cylinder and an upstanding barrel portion, a cylinder head cover through which said barrel projects, a sealing ring between the cover and barrel, and a member intermediate the cover and cylinder head supporting the sealing ring and being constructed and arranged for cooperation with the cylinder head to form a water conducting and water deflecting passage.

4. An internal combustion engine of the sleeve valve type comprising a water jacketed cylinder, a piston operable therein, a water jacketed cylinder head forming a sleeve pocket with the cylinder, a cylinder head cover,

sealing means between the cover and cylinder head, and a member cooperating with the cylinder head water jacket to form a conduit for the cooling water, said member supporting said sealing means.

5. An internal combustion engine of the sleeve valve type comprising a water jacketed cylinder, a piston operable therein, a water jacketed cylinder head forming a sleeve pocket with the cylinder, a cylinder head cover, sealing means between the cover and cylinder head, a member cooperating with the cylinder head water jacket to form a conduit for the cooling water, said member supporting said sealing means, and means engaging the cylinder head for seating the cover and sealing means.

6. In a sleeve valve engine, a jacketed cylinder, a cylinder head having an annular jacket depending in the cylinder, a cylinder head cover, and a member beneath the cover overlying substantially all of the annular cylinder head jacket, said member communicating with the cylinder jacket to receive

25 water therefrom.

7. In a sleeve valve engine, a jacketed cylinder, a cylinder head having an annular jacket depending in the cylinder, a cylinder head cover, a member beneath the cover overlying the annular cylinder head jacket, said member communicating with the cylinder jacket to receive water therefrom, and a sealing ring for the cylinder head and cover supported by the said member.

35 8. In a sleeve valve engine, a jacketed cylinder, a cylinder head having a jacket depending in the cylinder, a cylinder head cover, and a member bridging the cylinder head jacket to either side of the longitudinal plane of the engine containing the cylinder head axis and forming a water conduit with the cylinder head jacket.

9. In a sleeve valve engine, a jacketed cylinder, a cylinder head having a jacket portion depending in the cylinder and having an upstanding barrel, a cylinder head cover through which the barrel extends, sealing means for the barrel and cover, and a member surrounding the barrel beneath the cover overlying substantially all of the cylinder head jacket portion and forming with the cylinder head jacket a water conduit receiving water from the cylinder jacket.

45 10. In a sleeve valve engine, a jacketed cylinder, a cylinder head having a jacket depending in the cylinder and having an upstanding barrel, a cylinder head cover through which the barrel extends, sealing means for the barrel and cover, and a member surrounding the barrel beneath the cover overlying substantially all of the cylinder head jacket and forming with the cylinder head jacket a water conduit receiving water from the cylinder jacket said member having

50 water outlet openings.

11. In a sleeve valve engine, a jacketed cylinder, a cylinder head having a jacket depending in the cylinder and having an upstanding barrel, a cylinder head cover through which the barrel extends, sealing means for the barrel and cover, and a member surrounding the barrel beneath the cover overlying the cylinder head jacket and forming with the cylinder head jacket a water conduit receiving water from the cylinder jacket, said member supporting said sealing means.

12. In a sleeve valve engine, a jacketed cylinder, a cylinder head formed with a water jacket depending in the cylinder and having a flanged portion seating on the cylinder, baffles positioned across the cylinder head water jacket terminating short of the bottom of the cylinder head water jacket and extending upwardly above the cylinder head flange, and means forming with the cylinder head water jacket a water conduit communicating with the cylinder jacket and cooperating with the said baffles for deflecting water downwardly into the cylinder head water jacket on one side of said baffles and upwardly on the other side thereof.

13. In a sleeve valve engine, a jacketed cylinder, a cylinder head formed with a water jacket depending in the cylinder and having a flanged portion seating on the cylinder, baffles positioned across the cylinder head water jacket terminating short of the bottom of the cylinder head water jacket and extending upwardly above the cylinder head flange, and means forming with the cylinder head water jacket a water conduit communicating with the cylinder jacket and cooperating with the said baffles for deflecting water downwardly into the cylinder head water jacket on one side of said baffles and upwardly on the other side thereof, said upwardly extending portions of said baffles terminating beneath and adjacent the said water conduit forming means.

14. In a sleeve valve engine, a jacketed cylinder, a cylinder head formed with a water jacket depending in the cylinder and having a flanged portion seating on the cylinder, baffles positioned across the cylinder head water jacket terminating short of the bottom of the cylinder head water jacket and extending upwardly above the cylinder head flange, said baffles also having lateral portions extending upwardly from the cylinder head flange, and means forming with the cylinder head water jacket a water conduit communicating with the cylinder jacket and cooperating with the said baffles for deflecting water downwardly into the cylinder head water jacket on one side of said baffles and upwardly on the other side thereof.

15. In a sleeve valve engine, the combination with a cylinder of a cylinder head having a first wall depending into the cylinder and

spaced therefrom to form a sleeve pocket, a second wall spaced within the first to form a water jacket and connecting therewith at the lower ends of the walls, said first wall terminating at its upper end in a lateral flange 5 seating on the cylinder, and spaced baffles joining the said walls to divide the water jacket into two portions, said baffles terminating downwardly short of the water jacket bottom and extending upwardly above the cylinder head flange to provide a water deflecting baffle portion.

16. In a sleeve valve engine, the combination with a cylinder of a cylinder head having a first wall depending into the cylinder and spaced therefrom to form a sleeve pocket, a second wall spaced within the first to form a water jacket and connecting therewith at the lower ends of the walls, said first wall terminating at its upper end in a lateral flange 15 seating on the cylinder, and spaced baffles joining the said walls to divide the water jacket into two portions, said baffles terminating downwardly short of the water jacket bottom and extending upwardly above the cylinder head flange to provide a water deflecting baffle portion.

17. In a sleeve valve engine, a cylinder, a cylinder head having a flange seating on the cylinder and provided with a jacketed portion spaced from and depending within the cylinder, said cylinder head provided with an upstanding barrel formed with a sealing ring supporting flange, a sealing ring surrounding the barrel supported by said barrel flange and forming a water seal for the barrel and cylinder head cover, and a baffle for the cylinder head jacket extending downwardly into the depending portion of the jacket and upwardly and laterally therefrom above the cylinder head flange, said upwardly extending portion joining the barrel flange.

18. In a sleeve valve engine, a cylinder, a cylinder head having a flange seating on the cylinder and provided with a jacketed portion spaced from and depending within the cylinder, said cylinder head provided with an upstanding barrel, a cylinder head cover through which the barrel extends, a sealing ring surrounding the barrel and forming a water seal for the barrel and cylinder head cover, and a baffle for the cylinder head jacket extending downwardly into the depending portion of the jacket and upwardly therefrom above the cylinder head flange, said upwardly extending portion terminating below the sealing ring.

19. In a sleeve valve engine, a cylinder, a cylinder head having a flanged portion seated on the cylinder and formed with a water jacket depending in the cylinder, and a water deflecting baffle over said depending water jacket extending upwardly above the cylinder head flange, said baffle bridging the water jacket to either side of the cylinder head axis.

20. In a sleeve valve engine, a cylinder, a

cylinder head having a flanged portion seated on the cylinder and formed with a water jacket depending in the cylinder, and a water deflecting baffle over substantially the whole of said depending water jacket and extending upwardly and laterally to a position overlying the cylinder head flange.

21. In a sleeve valve engine, a jacketed cylinder, a cylinder head having a jacket depending in the cylinder, a cylinder head cover, a member bridging the cylinder head jacket and forming a water conduit with the cylinder head jacket, and a baffle cooperating with said member for deflecting water into the cylinder head jacket.

In witness whereof, I hereunto subscribe my name this 14th day of November, A. D. 1927.
